DRIVING DEVICE FOR MINIATURE GOLF BALLS

Filed Feb. 16, 1928

By

E. W. Board

Attorney

UNITED STATES PATENT OFFICE.

HENRY J. KLUTHO, OF JACKSONVILLE, FLORIDA.

DRIVING DEVICE FOR MINIATURE GOLF BALLS.

Application filed February 16, 1928. Serial No. 254,740.

My invention relates to a golf club or device for driving a miniature golf ball by the use of which a game of golf may be played in limited areas indoors or out of doors and it is an object of my invention to provide a device of this character by means of which a miniature golf ball may be driven as in the usual game of golf with the player in the same position as in such game and without requiring that he get on his knees or assume a tiresome position, all as will be hereinafter described and claimed.

Referring to the accompanying drawings which are made a part hereof and on which similar reference characters indicate similar parts,

Figure 1 is a side elevation illustrating one application of my invention,

Figure 2, a front elevation showing the club in retracted position ready for a drive,

Figure 3, a fragmentary side elevation of a rotary head for holding three golf clubs, and

Figure 4, a front elevation of the rotary head of Fig. 3.

In the drawings reference character 10 indicates a handle which preferably corresponds to the handle of an ordinary golf club but which may be of a cheaper construction.

To the lower portion of the handle 10 is secured a frame consisting of a rod or body 11 having an upper bracket or cross arm 12 and a lower bracket 13 both of which engage the handle 10 for securing the handle in fixed relation to the member 11. The upper bracket 12 is provided with an eye or ring 14 at its outer end through which the handle extends and is held in said ring by means of a screw 15. In like manner the lower bracket 13 is provided with a smaller eye or ring 16 which forms a socket for the reception of the lower extremity of the handle 10.

The lower end of the rod 11 is provided with a pair of diverging legs 17 having rubber tips 18 for supporting the device on the carpet or surface upon which the game is played. The legs 17 are disposed in a plane at right angles to a plane passing through the handle 10 and rod 11 or in parallel relation to the person using the club. A spring blade 19 is mounted in a longitudinal slot 20 in an adjustable arm 21, said slot being of a size to snugly receive the spring blade. In order to hold the blade in position the upper bracket or cross

arm is provided with an extension which overlies the slot in the adjustable arm 21 but is of a width so that its edge is slightly offset whereby when the blade is in the slot it will be held slightly bent to one side and cause the blade to be firmly held but permitting it to be moved freely longitudinally or pivoted in the slot 21. The edge of the overhanging extension is slightly beveled so that it presents a flat surface 22 to the spring blade 19. To the lower end of the blade is attached, by any desired means, a miniature golf club 23 which may be of any desired form and which may be either permanently attached to the blade or detachably connected thereto. In its natural position the blade is suspended perpendicularly with the club supported at a slight angle for addressing the ball.

Means is provided for tensioning the blade by drawing it sidewise to permit it to perform the driving operation which means comprises a rocker arm 25 supported upon a pivot 26 mounted on the rod 11. The rocker arm 25 is provided with an elongated transverse portion 27 at its free end on which are mounted a pair of slightly spaced parallel pins 28 which are disposed upon opposite sides of the spring blade 19. On the opposite side of the transverse portion 27 is mounted a pin or stud 29 to which is attached an operating wire or cord 30. The operating wire 30 has its upper end attached to the lower end of a lever 31 which is mounted in a pair of eye screws 32 spaced longitudinally of the handle 10 and having an outwardly turned portion or finger piece 33 adapted to be operated for swinging the rocker arm and drawing the blade to one side for tensioning the same whereupon it may be released by allowing it to slip off the end of the finger for effecting the driving operation. The lever 31 is preferably provided with a curved handle engaging element which serves to maintain the lever in proper position and also as a stop to limit the passage of the lever through the eye screws. The releasing of the finger piece snaps the blade into action and causes the miniature golf club to strike the ball and send it off into flight, the force of the drive of course being determined by the amount of the spring blade is distorted or bent by pulling up the lever.

The blade can be easily lowered or raised, moved sidewise, or pivoted within the slot 20 of the adjustable arm in order to reach a ball

that may have a bad lie, be near a bunker, or in a hole, the arm 21 being adjustable so that the amount of the stroke can be varied by the varying of the arc of the blade.

5 If the miniature golf sticks are permanently affixed to the spring blades, a number of blades will be required, however, as shown in Figs. 3 and 4, I have provided the blade 35 with a support 36 having radial ribs 37 10 for cooperation with grooves 38 in a rotary head 39 carrying, for the purpose of illustration, three clubs such as for example a driving iron 43, niblick 44 and putter 45, which may be brought into position by a 15 mere rotation of the head. The support 36 and head 39 are held in resilient contact by means of a spring 40 and a bolt 41 passing through the spring and into the member 36. The rotary head is provided with sockets 42 20 for the reception of the golf sticks 43, 44 and 45 above mentioned.

It will be obvious to those skilled in the art that various changes may be made in my device without departing from the spirit of 25 the invention, and I, therefore, do not limit myself to what is shown in the drawings and described in the specification, but only as set forth in the appended claims.

Having thus fully described my said invention, what I claim as new and desire to 30 secure by Letters Patent, is:

1. A device for driving a golf ball comprising a handle, a body fastened to said handle, a flat spring member carried by said body, a driving iron mounted on the end of 35 said flat spring member, and means for drawing said spring member sidewise whereby the same may be released to permit it to perform the driving operation, substantially as set forth.

2. The combination of a handle, a frame carried by said handle, a longitudinally disposed flat spring member supported by said frame, a driving iron mounted on the lower 45 end of the spring member, and means for drawing the spring member sidewise so that it may be released to swing the driving iron in an arc, substantially as set forth.

3. The combination in a device for playing miniature golf, of a frame, legs at the lower end of the frame for supporting the same, a handle attached to the frame, a flat spring blade disposed longitudinally of the frame, a miniature golf club carried by the 50 lower end of the spring, a rocker arm pivoted on the frame, and a pair of pins mounted on said rocker arm and arranged on opposite sides of the flat spring whereby when the rocker arm is rotated it will flex the 55 spring sidewise so that its release will perform an operation similar to that of driving a standard golf ball, substantially as set forth.

4. The combination of a frame, a handle 60 attached to the frame, a bracket adjustably

mounted on the frame and provided with a longitudinal slot, a flat spring blade in said slot, means above the adjustable member in alignment therewith engaging the spring blade and holding the same in a slightly flexed position, a rocker arm pivoted on said frame, pins mounted in parallel relation on said rocker arm and engaging opposite sides of said spring, an operating cord connected to said rocker arm and adapted to be pulled for rotating the rocker arm on its pivot for flexing the blade and adapted to be released for permitting the blade to snap back into normal position, and a miniature golf club carried at the lower free end of the spring 80 70 75 85 90 95 100 105 110 115 120 125 130 135 140 145 150 155 160 165 170 175 180 185 190 195 200 205 210 215 220 225 230 235 240 to said support to vary the length of the stroke and the inclination of the driving member, resilient means tending to maintain said driving member in adjusted position, and a manipulating element having connection with the driving member whereby the driving member may be actuated to simulate

the driving movement of a golf club, substantially as set forth.

In witness whereof, I have hereunto set my hand at Washington, District of Columbia, this fourteenth day of February, A. D. 1928.

HENRY J. KLUTHO.
